UNITED STATES PATENT OFFICE.

DAVID G. MELVILLE, OF MEDFORD, MASSACHUSETTS, ASSIGNOR TO ROXBURY CARPET COMPANY, OF BOSTON, MASSACHUSETTS, A CORPORATION OF MASSACHUSETTS.

DESIGN FOR A RUG.

43,008.

Specification for Design. Patented Sept. 10, 1912.

Application filed June 26, 1912. Serial No. 706,093. Term of patent 3½ years.

To all whom it may concern:

Be it known that I, DAVID G. MELVILLE, a citizen of the United States, residing at Medford, in the county of Middlesex and State of Massachusetts, have invented a new, original, and ornamental Design for Rugs, of which the following is a specification, reference being had to the accompanying drawing, forming part thereof, on which the figure is a plan view of a portion of a rug showing my new design.

I claim:

The ornamental design for a rug as shown.

DAVID G. MELVILLE.
